APRON

Pauline Goldsmith, New York, N. Y.

Application February 8, 1946, Serial No. 646,228

1 Claim. (Cl. 2-48)

1 My invention relates to a new and improved apron, which is open at its rear and which is provided with a neck-spring and also with a waist spring for detachably holding the apron on the body of the user, at the neck and waist.

The improved apron can be made at low cost, and the respective springs can be easily removed and replaced, when the apron is laundered and ironed.

Other objects and advantages are stated in the annexed description and drawings, which illustrate a preferred embodiment thereof.

Fig. 1 is a front perspective view of the improved apron, with the neck spring held vertical.

Fig. 2 is a section on the line 2-2 of Fig. 1.

Fig. 3 is a rear perspective view of a part of the apron. The neck spring is shown in vertical position, and the waist spring is shown in horizontal position. The representations of parts of the rear fabric layers are omitted.

Fig. 4 is a section on the line 4-4 of Fig. 1.

Fig. 5 is a top perspective view of the neck spring.

Fig. 6 is a section on the line 6-6 of Fig. 5.

The body of the apron is made of a front body-layer 1 of fabric or other material. Said front body-layer 1 has outer marginal edges, and it is cut out at its top between its respective longitudinal marginal edge-portions to provide a neck opening N, which has a curved edge, which is joined to the respective marginal edge-portions of the body-layer 1, by transverse and separate edge-portions 2a and 2b, so that the neck opening N is open at its rear. The entire apron is open at its rear.

The marginal edges of the body-layer 1, including the curved edge-portion of the neck opening N and its separate edge-portions 2a and 2b, are finished by a fabric strip or tape 2, which is folded at its outer edge to provide two layers of tape-fabric. Said doubled tape 2 also encloses the adjacent respective edge-portions of a rear, supplemental layer of fabric or other material 10, which forms a rear neck-pocket for receiving the neck spring 4, in combination with the front body-layer 1.

Said rear layer 10, above its transverse bottom edge 10a, has the same contour as the respective part of the front body-layer 1, including the edge-portion of its curved neck opening and the separate edge-portions 2a and 2b of said layer 1 at the rear of said neck opening N.

The stitches 14 connect the edge-tape 2 to all the edges of the body-layer 1, including the curved edge-portion of its neck opening N, and

5 the separate edge-portions 2a and 2b. Said doubled tape 2 also connects the layer 1 to all the edge-portions of the rear layer 10, with the exception of the bottom transverse edge 10a of layer 10, which is horizontal in Fig. 3.

Close to the horizontal bottom edge 10a of the rear layer 10, said rear layer 10 is connected to the body-layer 1 by horizontal stitches 11, which are interrupted, in order to provide a bottom opening 12 for said rear neck-pocket. The neck spring 4 is a split ring which is made of resilient metal or other springy material. It has a cylindrical body, whose ends 5a and 5b are bent reversely, to provide respective loops. These loops provide enlarged ends of the neck spring 4. The ends of said loops abut the body of the neck spring 4.

Between said loops, the body of the neck spring 4 is cylindrical and said body is located in a single plane. The end-loops are substantially perpendicular to said plane.

15 When the ends 5a and 5b are forced to contact each other by flexing the neck spring 4 out of its normal shape of Figs. 5 and 6, the cylindrical body of said neck spring is substantially an annulus whose inner circumferential surface element is the circumference of a circle.

In normal shape, the enlarged ends 5a and 5b are slightly separated from each other. These separate ends 5a and 5b can be readily forced 20 away from each other, out of their normal positions of Figs. 5 and 6, by flexing the body of the neck spring out of its normal annular shape.

In order to insert the neck spring 4 into operative position, its end 5a, for example, can be inserted into the neck-pocket, through the bottom opening 12 of said neck-pocket. This can be done without flexing the neck spring 4 out of its normal shape.

The neck spring 4 is then turned relative to 25 the neck-pocket, without flexing said neck spring 4 out of its normal shape, until the end 5a of said neck spring 4 abuts the edge-portion 2b of said neck-pocket. The upper part of the apron is then bent, while turning the neck-spring 4 30 without flexing it, until the exposed end 5b is below the bottom opening 12 of the neck-pocket, while the end 5a is located at the corner between the edge-portion 2b and the curved edge-portion of the neck-pocket.

The neck spring 4 is then slightly flexed, so as to insert the exposed end 5b into the neck-pocket, through its bottom opening 12.

The neck spring 4 is then turned relative to the neck-pocket, until the enlarged ends 5a and 5b substantially abut the corners between the

edge-portions **2a** and **2b** and the curved edge-portion of the neck opening **N**. The body of the neck spring **4** then substantially abuts the curved edge-portion of the neck opening **N**.

The edge-portions **2a** and **2b** are then yieldingly held in substantially abutting position.

The opening **12** is of sufficient width, so that when it is desired to remove the neck spring **4** from the neck-pocket, the body of said neck spring **4** can be easily turned without flexing it, until one of the ends **5a** or **5b** is moved out of the neck-pocket through the bottom opening **8**, with only slight flexure of said neck spring **4**. The neck spring can then be easily slid out of the neck-pocket. Either end of the neck spring **15** can be initially inserted or removed.

The improved neck-pocket is much superior to an ordinary hem, because it is possible to use a neck spring which has substantially enlarged ends **5a** and **5b** of smooth contour, and to use a neck spring which is substantially a continuous annulus, when said neck spring is in normal shape.

As an example, when the neck spring **4** is in normal, unflexed shape, the internal diameter of its body is approximately 6.25 inches; and the distance between the enlarged ends is about 0.5 inch. The width of the bottom opening **12** is about 6 inches. At the edge **10a**, the width of the apron is about 10-11 inches.

Hence the width of the bottom opening **12** is substantially equal to the normal diameter or maximum width of the body of the neck spring, whose thickness is small. The slight excess of the normal internal diameter of the neck spring **4**, over the width of the bottom opening, **12**, prevents the neck spring **4** from falling out of the neck-pocket.

At its waist, the garment has a hem **H**, which is closed at its ends, and which has two openings **8** adjacent and intermediate its closed ends.

Said hem **H** is formed by a supplemental rear layer of fabric **15**, which is stitched to layer **1** by top stitches **6** and bottom stitches **7**. Stitches **6** may be a continuation of stitches **14**, which connect the two layers of the folded edge-tape **2** to each other and to the intermediate layer **1**.

The waist spring **9** is a resilient, split steel ring or band, which has smooth ends, so that it can be readily inserted into and removed from hem **H**, through either of the hem-openings **8**.

The springs **4** and **9** can be easily transversely enlarged or expanded by flexing their free ends away from each other, in order to put the apron on and to take it off, thus eliminating buttons, zippers, and other fastening devices.

These springs releasably engage the neck and waist of the user.

The two layers of the neck-pocket are unconnected to each other, save by the edge-tape **2** and the stitches **11**.

I have described a preferred embodiment of my invention, but numerous changes and omissions and additions can be made without departing from its scope.

The spring **9** at the waist may have the same construction as the neck-spring **4**. The reversely-bent ends **5a** and **5b** may abut the cylindrical body of the wire **4**, instead of being in loop-form. The shape of the neck-opening may be any desired shape, with a corresponding change in the shape of the neck-spring **4**.

I claim:

An apron which comprises a body-layer of fabric, said body-layer having outer longitudinal marginal edges at the top portion of said body-layer, said body-layer having a cut-out which provides a neck-opening between said marginal edges at the top of said apron, said body-layer having separate edges at the rear of said neck-opening, a supplemental layer of fabric which is located at the rear of said body-layer, said supplemental layer extending transversely across the respective part of said body-layer, the bottom-edge of said supplemental layer being below said neck-opening, said supplemental layer having a cut-out which coincides with said first-mentioned cut-out, said supplemental layer and said body-layer being continuously stitched to each other at the edges of said cut-outs and at said longitudinal marginal edges, said bottom edge being stitched to the body-layer by transverse stitches which are interrupted substantially at the median point of said bottom edge, a blade neck-spring which is located between said layers and which abuts the connected edges of said cut-outs, said neck-spring being shaped to be inserted between said layers and to be removed from its position between said layers at said median point.
